UNITED STATES PATENT OFFICE.

CARL E. BROWN, OF COLUMBUS, OHIO, ASSIGNOR TO UNITED STATES MANUFACTURING COMPANY, OF COLUMBUS, OHIO.

OIL-BURNER.

1,118,916.

Specification of Letters Patent.

Patented Dec. 1, 1914.

Application filed August 20, 1914. Serial No. 857,733.

To all whom it may concern:

Be it known that I, CARL E. BROWN, a citizen of the United States, residing at Columbus, in the county of Franklin and State of Ohio, have invented a new and useful Oil-Burner, of which the following is a specification.

The present invention appertains to liquid fuel or hydro-carbon burners, and aims to 10 provide a novel and improved burner adapted to be utilized in a convenient and effective manner within the fire box of a cook stove, although it is to be understood, at the outset, that the present burner may be employed in various capacities for heating purposes.

It is the object of the invention to provide a hydro-carbon burner applicable to the fire boxes of cook stoves, and embodying 20 a swingably mounted retort or generator adapted to be heated by the flames, and whereby the flames may be directed in various manners, as desired, without interfering with the heating of the retort or generator, 25 so that when the burner is applied to the fire box of a cook stove, the flames may be either directed upwardly through the lid openings or against the lids of the top of the stove, or may be directed rearwardly 30 over the oven to heat the oven effectively and with a minimum amount of fuel.

Another object of the present invention is to provide a burner having a priming device or means, to and from which the generator or retort is movable, in order that the 35 burner may be readily primed when the retort or generator is swung immediately over the priming device.

It is also within the scope of the present 40 invention, to provide a unique assemblage of component parts, whereby the utility of the burner will be enhanced, and the burner rendered thoroughly practical and efficient.

With the foregoing and other objects in 45 view which will appear as the description proceeds, the invention resides in the combination and arrangement of parts and in the details of construction hereinafter described and claimed, it being understood that 50 changes in the precise embodiment of the invention herein disclosed, can be made within the scope of what is claimed without departing from the spirit of the invention.

The invention has been illustrated in its

preferred embodiment in the accompanying drawing, wherein:

Figure 1 is a plan view of the improved burner. Fig. 2 is a rear view thereof. Fig. 3 is a cross section thereof, taken on the line 3-3 of Fig. 2, and illustrating the same applied within the fire box of a cook stove.

In carrying out the present invention, there is provided a cast metal base plate 1 which has its rim engaging over the upper edge of a sheet metal shell 2 which forms 65 an air chamber therein, the shell 2 being seatable upon the grate within the fire box of a cook stove, and serving to direct the air upwardly from the grate to the flames, as will hereinafter appear.

The plate 1 is provided with a pair of openings 3, and with integral domes 4 disposed over the openings 3. The plate 1 may be provided with any number of the openings 3 and domes 4, according to the length 75 of the burner, the use of two or more openings 3 and domes 4 being a mere duplication or multiplication. The plate 1 is also provided with a depressed channel or gutter 5 extending longitudinally thereof along its 80 rear edge and in rear of the openings 3 and domes 4, the gutter or channel 5 serving as an elongated priming cup which may hold asbestos, ashes, or other absorbent material for the liquid fuel.

There is provided a U-shaped pipe 6 having its arms disposed horizontally, the lower arm 7 of the pipe 6 being journaled through the sides of the domes 4, longitudinally of the burner body constituting the 90 plate 1 and shell 2. The arm or limb 7 of the pipe 6 serves as a vapor tube, while the other arm or limb 8 of the pipe 6 which is disposed above the domes 4, serves as the retort or generator. The arm or vapor tube 95 7 being journaled through the sides of the domes 4, enables the retort or generator 8 to be swung above the domes to and from the priming cup or gutter 5.

In order to supply oil or other suitable 100 liquid fuel to the retort or generator 8, a pipe 9 is attached to the free end of the retort or generator 8, and extends to the axis of the arm or vapor tube 7, and a pipe 10 which is in alinement or coaxial with the 105 arm or tube 7, is attached to the pipe 9, and has attached thereto, a suitable controlling valve 11. The pipe 10 is adapted to be jour-

naled through one end or side of the fire box, whereby the valve 11 will be disposed exteriorly of the stove to be readily controlled and to be swung for oscillating the retort or generator 8. The valve 11 may be connected by a flexible supply pipe or conductor 11^a to a liquid fuel tank or other source of fuel.

10 A cap or closure 12 is engaged over the free end of the arm or tube 7, and the said arm or tube 7 is preferably supported by ears or seats 13 upstanding from the ends of the plate 1.

15 The vapor tube 7 is provided with lateral outlet apertures 14 within the domes 4, and directed toward the retort 8, and the domes 4 are provided with upper openings 15 and rear openings or slots 16 through which the vapor or gas may pass from the apertures 20 14 of the vapor tube 7. The vapor outlet apertures 14 therefore coöperate with the openings 15 and 16 of the domes 4, to enable the jets or streams of gas issuing from the apertures 14 to pass through the respective openings 15 and 16 according to the 25 position of the retort.

30 Spreaders 17 are carried by the retort or vaporizing tube 8, the spreaders 17 having the collars 18 embracing the retort 8, and the spreaders 17 being so arranged with respect to the apertures 14, that the flames will impinge against the spreaders 17 to be spread thereby over a considerable area.

35 In order to enable a small quantity of the liquid fuel to be discharged into the priming cup 5, from the vapor tube 7, inclined troughs 19 of sheet metal or other suitable material, have their lower ends secured in any suitable manner to the outer side of the 40 priming cup 5 at the lower ends of the openings or slots 16, and project below the vapor tube 7 above the openings 3, whereby the upper ends of the troughs 19 lie below the apertures 14. Thus, any oil or liquid 45 fuel which is permitted to spurt or flow through the apertures 14, will be caught by the troughs 19 and conducted into the priming cup or channel 5.

50 A bracket 20 is terminally secured to the forward and rear edge portions of the plate 1 between the two domes 4, and is provided with an upper notch 21 over which the retort 8 is engageable when the retort is swung upwardly, and the rearward portion of the 55 notched bracket 20 is provided with a seat or shoulder 22 against which the retort 8 is seatable when the retort is swung to its lower or rearward position.

55 In use, the burner may be readily applied 60 within the fire box 23 of a cook stove, as suggested in Fig. 3, with the priming cup 5 disposed adjacent the back of the fire box, and with the pipe 10 journaled through the corresponding end or side of the fire box. 65 The valve 11 is flexibly connected to the fuel

tank or other source of fuel, to enable the burner pipe 6 to be swung back and forth. To prime the burner, the valve 11 is swung at the outside of the stove, to bring the retort 8 above the priming cup 5, as indicated 70 by dotted lines in Fig. 3, and then, by opening the valve 11, the oil or other liquid fuel may be admitted into the pipe 6. The oil or fuel will then spurt or flow through the apertures 14 and will be conducted into the 75 priming cup by the conveyers 19. The fuel within the priming cup 5 may then be ignited, which will cause the retort 8 to be heated for starting the vaporization of the liquid fuel. The vapor generated within the 80 retort 8 will then pass into the vapor tube 7 and out through the apertures 14 to support the flames, the flames impinging against the spreaders 17 to be spread thereby, and to continue the heating of the retort during 85 the operation of the burner. As the vapor is emitted from the apertures 14 and consumed, air will be drawn up through the shell 2 and through the openings 3 to the domes 4, wherein the air will be admixed 90

with the vapor to provide a thoroughly combustible mixture. After the burner has been started, the retort 8 can be swung upwardly and downwardly, as desired. When the retort 8 is swung upwardly, it will lie below the stove lids 24 or the lid openings, for effectively heating the vessel or vessels placed upon the stove, and when the retort 8 is swung downwardly, as seen in dotted lines in Fig. 3, the flames will shoot over the oven 100 25 for thoroughly and quickly heating the oven for baking or kindred purposes. When the retort 8 is swung upwardly, the flames will pass through the openings 15 of the domes 4, while when the retort 8 is swung downwardly, the flames will pass through the openings or slots 16. In this manner, the flames may be either directed upwardly or in an inclined manner over the oven 25, 105 which will enable the burner to be readily used for either cooking or baking purposes, with the least amount of fuel. Furthermore, the movement of the retort enables the burner to be conveniently primed, as above 110 intimated.

115 The present burner is comparatively simple and inexpensive in construction, and is thoroughly practical and efficient in operation, the other advantages and capabilities of the device being obvious to those versed in the art, it is thought, without further comment being deemed necessary.

Having thus described the invention, what is claimed as new is:—

1. In a hydro-carbon burner, a base having a priming cup, a vapor tube journaled to the base, and a retort connected to the vapor tube and arranged to swing to and from the priming cup, the vapor tube having an outlet directed toward the retort. 125 130

2. In a hydro-carbon burner, a base having a priming cup, and a U-shaped pipe having one arm journaled to the base so that the other arm is movable to and from the priming cup, the first mentioned arm of the pipe having an outlet directed toward the last mentioned arm, and the last mentioned arm forming a retort.
3. In a hydro-carbon burner, a base, a U-shaped pipe having one arm journaled thereto, the said arm of the pipe having an outlet directed toward the other arm, and the last mentioned arm of the pipe serving as a retort, and a bracket carried by the base and coöperable with the last mentioned arm of the pipe for holding it at various adjusted positions.
4. In a hydro-carbon burner, a base having an opening therein and a priming cup adjacent the said opening, a vapor tube journaled upon the base and projecting over the said opening, a retort connected to the vapor tube to swing therewith, the vapor tube having an outlet directed toward the retort, and a trough carried by the base and extending from below the said outlet to the priming cup.
5. In a hydro-carbon burner, a base, a U-shaped pipe having one arm journaled upon the base, the said arm of the pipe having an outlet directed toward the other arm, and the last mentioned arm of the pipe serving as a retort, a connecting pipe connected to the free end of the retort arm of the aforementioned pipe and disposed coaxial with the journaled arm of the said pipe, and a valve connected to the connecting pipe and adapted for connection with a source of fuel.
6. In a hydro-carbon burner, a base having an opening and a dome thereover, a vapor tube journaled through the sides of the dome, and a retort connected to the vapor tube and adapted to swing above the dome, the vapor tube having an outlet within the dome and directed toward the retort, and the dome having an opening with which the said outlet coöperates.
7. In a hydro-carbon burner, a base having an opening and a dome thereover, and a U-shaped pipe having one arm journaled through the sides of the dome, the other arm of the said pipe serving as a retort, the first mentioned arm of the pipe having an outlet within the dome and directed toward the said retort arm, and the dome having an opening coöperating with the said outlet to permit of the passage of vapor therethrough.
8. In a hydro-carbon burner, a base having an opening, a dome thereover, and a priming cup adjacent the said opening, a vapor tube journaled through the sides of the dome, a retort connected to the vapor tube to swing therewith to and from the priming cup, the vapor tube having an outlet within the dome directed toward the retort, and the dome having openings coöperating with the said outlet, and a trough carried by the base and extending from below said outlet to the priming cup.
9. In a hydro-carbon burner, a base plate having openings, domes over the said openings, and a priming channel extending adjacent the said domes, the domes having upper openings and openings adjacent the said priming channel, a U-shaped pipe having one arm journaled through the sides of the said domes, the other arm of the said pipe serving as a retort, the first mentioned arm of the said pipe having outlet apertures within the said domes and directed toward the retort arm to direct the vapor through the said openings of the domes, and inclined troughs having their lower ends secured to the said priming channel and having their upper ends projecting below the outlet apertures.
- In testimony that I claim the foregoing as my own, I have hereto affixed my signature in the presence of two witnesses.
